FACE HARNESS FOR MICROPHONES

Herman C. Hornickel, Fair Haven, N. J.

Application October 5, 1943, Serial No. 505,022

8 Claims. (Cl. 179—156)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to a harness for supporting a small microphone, and particularly for supporting a small microphone above the mouth of the individual in combination with various types of protective headgear or protective facial covering.

According to conventional use, microphone supporting harness is not easily adapted to use with gas masks or helmets.

Generally, where microphones are used in connection with helmets, gas masks, or respirators, the microphone is conventionally made a part of the helmet, gas mask, or respirator. Such an assembly would naturally tend to be heavy and awkward. The added inconvenience exists that when removing the helmet or other headgear the microphone is also removed.

While it is true that the throat microphone frees the hands and can be worn apart from the mask or other face covering—it suffers from the objection that complete intelligibility is not possible because its acoustic range is limited.

In some industrial applications where respirators are essential in carrying on the work and where the noise level is high, conversation between workers must be carried on by the use of microphones and same is usually made a part of the respirator unit.

In general, the use of microphones in connection with helmets, gas masks, respirators or other types of protective headgear, the addition of a microphone to these units results in added discomfort and unnecessary fatigue.

There are many other applications, similar to those just mentioned which are familiar to those skilled in the art, that may cause discomfort and distress to the wearer of such equipment.

The object of this invention, therefore, is to overcome the disadvantage of added weight of present type of harness.

A further object is to provide a harness that will permit the use of a microphone close to the source of sound.

Another object is to afford the use of a harness that can be worn under a gas mask, helmet, respirator or other type of protective headgear and facial covering and where the removal of said headgear will not deprive the wearer of the use of the microphone.

A still further object is to provide a micro-

2

phone harness adjustable to the head size of any wearer.

In accordance with this invention, numerous advantages are made possible because of its unique design. Application of the invention to industrial uses and more particularly to work carried on in locations where a high level of noise maintains is very favorable.

It has been the practice under the aforementioned conditions to resort to chest type supported microphones. It will be obvious to those skilled in the art that this type of microphone harness is cumbersome and a latent danger of interference in the movements of the worker exists.

However, the invention definitely overcomes this disadvantage. Its unique construction permits placement of the microphone, for which this invention was designed, on the face of the user and in close proximity to his mouth. The close proximity of the microphone to the source of sound is important if intelligible conversation is to be carried on with a minimum of effort and a maximum of concentration on the task on which the worker is employed.

In some industrial applications, in addition to the use of a microphone, a face mask is used by the worker. Here, the advantage of the invention resides in the fact that any type of facial protection may be used without interference in the use of the microphone and conversely the removal of the mask would not interfere with the continued use of the microphone. In conventional practice the microphone is made a part of the mask. The advantage of the invention in this respect is obvious.

So adaptable is the invention that interference with any type of protective headgear or protective covering is impossible and any type of protective covering may be used in conjunction with the invention.

The invention lends itself admirably to speech amplification in connection with instructions in surgery as the device can be worn under the anti-septic face covering used by the surgeon and assistants without the slightest impairment of free movement and with a high degree of comfort.

The ease with which the invention can be placed on the face of the wearer and its ready adaptability to all types of facial contours is a very definite advantage.

It will be apparent to those skilled in the art that many applications of the invention are possible.

For a better understanding of the invention,

together with other and further objects thereof, reference is had to the following description, taken in connection with the accompanying drawings, and its scope will be pointed out in the appended claims.

In the accompanying drawings are illustrated various parts of the invention as follows:

Figure 1 illustrates that part of the invention which is placed over the right ear of the wearer,

Figure 2 is that portion of the invention which is placed over the left ear,

Figure 3 is an isometric view of the microphone bracket,

Figure 4 is a sectional view of the extrusion of the microphone bracket which retains the microphone in place,

Figure 5 is a partial plan view of the assembled invention,

Figure 6 is a view in elevation of the assembled invention including the microphone,

Figure 7 illustrates a view of the microphone for which this invention was designed and showing that side of the microphone which is in juxtaposition to the microphone bracket, Figure 3,

Figure 8 is a pictorial representation of the invention as used in connection with the microphone for which it was designed.

Referring now more particularly to Figure 1, the invention comprises a right hand strap 41 of molded flexible construction and a loop 43 which is embedded in strap 41 at point 42 and threaded through an orifice 44 in the strap 41. The strap 41 may preferably be of cotton cloth molded in "Vinylite" or it may be of rubber, leather or other suitable construction. The loop 43 is preferably a cotton cord similarly molded in "Vinylite." On the free end of loop 43 is attached a cylindrical covering 45 of sufficient diameter to prevent said loop 43 from slipping out of the orifice 44 in the strap 41. Molded into the said strap 41 is a two conductor cable 46 which extends out from the end 47 of strap 41 a predetermined distance. The two conductors 48 in cable 46 which extend out from the end 47 of strap 41 are bared to enable the soldering of same to the microphone Figure 7 in a manner to be described hereinafter. The cable 46 terminates in a plug 49 of standard manufacture and that part of the cable 46 which terminates in the said plug 49 extends from point 50 of strap 41. Pockets 51, 51 are provided for the insertion of the elongated tips 61, 61 of the microphone bracket Figure 3. In all respects with the exception of the inclusion of the two conductor cable 46 the left hand strap Figure 2 is identical to the right hand strap 54 illustrated in Figure 1 and comprises a loop 52 inserted at point 53 of strap 54 threaded through the orifice 55, the said loop 52 having appended to its free end a cylindrical covering 56 of sufficient diameter to prevent the free end of loop 52 from slipping out of the orifice 55 in the strap 54. As in Figure 1, the strap 54, Figure 2 contains a pocket 51 into which is inserted the microphone bracket Figure 3 as described above.

Figure 5 illustrates in plan view the invention when same is assembled and ready for use. The end portion 57, of strap 54 is cemented to the inner surface 60 of the microphone bracket Figure 3. The bared conductors 48 of cable 46 which extend from the end 47 of strap 41 are soldered to the input terminals 70 and 71 of the microphone Figure 7.

Referring now to the construction of the invention, straps 41 and 54 are molded of a substance which is flexible and non-hygroscopic. In

the molding processes the edges of straps 41 and 54 are formed to provide a knife-like edge 68. The insides of the straps 41 and 54 which rest against the face of the wearer are given a fine pebble-like surface the purpose of which is to

provide a certain amount of ventilation and thus reduce perspiration by reason of close contact of the straps 41 and 54 with the face. The microphone bracket Figure 3 is so designed that the extrusions 64, 64 grip the shoulder 72 of the microphone Figure 7. The extended portions 61 of the microphone bracket Figure 3 are inserted in the pockets 51, 51 of straps 41 and 54 and cemented therein. After the straps 41 and 54 and microphone bracket Figure 3 are assembled as indicated in Figure 5 the exposed conductors 48 of the cable 46 are soldered to the terminals 70 and 71 of the microphone Figure 7. The microphone Figure 7 is then snapped into the microphone bracket 62, as illustrated in Figure 6. The harness is placed over the face of the wearer (as shown in Figure 8) by slipping the loops 43, 52 (Figures 1 and 2) over the ears, said loops being enlarged in circumference for this purpose by pulling the loops through the orifices 44, 55. The harness may then be secured by decreasing the circumference of each loop 43, 52 by pulling downward on the coverings, 45, 56.

The ultimate result of this invention is to provide a microphone harness of such lightness, adjustability, and flexibility that it may be readily adapted to a large number of applications which are familiar to those versed in the art.

While there has been described what is at the present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A harness, designed to support a microphone, comprising a pair of light weight straps of flexible material having loops for supporting the harness on the ears of the wearer, each of said loops including a length of flexible cord fastened at one end to one of the straps and having an enlarged stopper at the other end, means to adjustably secure an intermediate portion of each of the cords to each of the straps so as to form a bight in each cord between its said fastened end and its said intermediate portion which bight is adjustable in length, a bracket adapted to support the said microphone, and means for joining the two straps to the bracket.

2. A harness, designed to support a microphone, comprising a pair of straps of flexible material having loops for supporting the harness on the ears of the wearer, each of said loops including a length of flexible cord fastened at one end to one of the straps and having an enlarged stopper at the other end, means to adjustably secure an intermediate portion of each of the cords to each of the straps so as to form a bight in each cord between its said fastened end and its said intermediate portion which bight is adjustable in length, a bracket adapted to support the said microphone, and means for joining the two straps to the bracket.

3. A harness, designed to support a microphone, comprising a pair of light weight straps for supporting the harness on the ears of the wearer, each strap being provided with a length

of flexible cord fastened at one end to one of the straps and having an enlarged stopper at the other end, means to adjustably secure an intermediate portion of each of the cords to each of the straps so as to form a bight in each cord between its said fastened end and its said intermediate portion which bight is adjustable in length, a bracket adapted to support the said microphone, and means for joining the two straps to the bracket.

4. A harness, designed to support a microphone, comprising a pair of straps for supporting the harness on the ears of the wearer, each strap being provided with a length of flexible cord fastened at one end to one of the straps and having an enlarged stopper at the other end, means to adjustably secure an intermediate portion of each of the cords to each of the straps so as to form a bight in each cord between its said fastened end and its said intermediate portion which bight is adjustable in length, a bracket adapted to support the said microphone, and means for joining the two straps to the bracket.

5. A microphone harness which can be worn on the face when suspended from the ears of the wearer constructed of flexible material comprising left and right straps, a microphone bracket sustained by said straps, left and right circumferentially adjustable loops attached to said straps respectively which permit tension to be applied to said straps, each of said loops including a length of flexible cord fastened at one end to one of the straps and having an enlarged stopper at the other end, means to adjustably secure an intermediate portion of each of the cords to each of the straps so as to form a bight in each cord between its said fastened end and its said intermediate portion which bight is adjustable in length.

6. A microphone supporting harness comprising a pair of straps of flexible non-hygrosopic material, loops of similar material adjustable in circumference to the wearer to apply tension to the straps, each of said loops including a length of flexible cord fastened at one end to one of the straps and having an enlarged stopper at the other end, means to adjustably secure an intermediate portion of each of the cords to each of the straps so as to form a bight in each cord between its said fastened end and its said intermediate portion which bight is adjustable in length, and a microphone bracket to which said straps are attached.

7. A harness to hold an electrical device close to a person's face, comprising two loops adapted to fit around the ears respectively, each such loop being adjustable in circumference so as to allow it to be placed over one ear and to be

tightened while positioned thereon, a strap joining said loops, means on said strap to support an electrical device, each such loop including a length of cord fastened at one end to the strap and having an enlarged stopper at the other end, means to adjustably secure an intermediate portion of each of said cords to the strap so as to form in each cord a bight between its said fastened end and its said intermediate portion which bight is adjustable in length.

8. A harness to sustain a microphone close to a wearer's upper lip comprising a strap member of flexible material, adapted to encircle the wearer's left ear and extend across the wearer's left cheek from the left ear to the vicinity of the left end of the upper lip, said strap being provided with three arms extending respectively substantially toward the upper portion of the left ear, the lower portion of the left ear and the left end of the upper lip, there being an aperture through the arm extending toward the lower portion of the left ear, said strap member also being provided with a cord, one end of which is secured to the arm extending toward the upper portion of the left ear and the other end of which is provided with an enlarged stopper, and the central portion of which runs through the aperture aforesaid, the stopper keeping said cord from running completely through said aperture; a second similar strap member, adapted to extend across the wearer's right cheek; a microphone bracket, secured to the arms extending toward the upper lip of the two strap members aforesaid, and adapted to sustain a microphone close to the upper lip; the harness being positioned over the wearer's face by placing the cords over the wearer's ears respectively and being adjustable to the wearer by pulling on the stoppers so as to shorten the length of cord extending about each ear.
